UNITED STATES PATENT OFFICE.

HENRY L. DIXON, OF DORMONT, PENNSYLVANIA, ASSIGNOR TO H. L. DIXON COMPANY,
OF CARNEGIE, PENNSYLVANIA, A CORPORATION OF PENNSYLVANIA.

ANNEALING LEER.

Application filed March 28, 1921. Serial No. 456,218.

To all whom it may concern:

Be it known that I, HENRY L. DIXON, a citizen of the United States, residing at Dormont, in the county of Allegheny and State of Pennsylvania, have invented a new and useful Improvement in Annealing Leers, of which the following is a full, clear, and exact description, reference being had to the accompanying drawings, forming part 10 of this specification, in which:

Figure 1 is a longitudinal section of a portion of a glass annealing leer embodying one form of my invention;

Figure 2 is a section on the line II—II of 15 Figure 1;

Figure 3 is a view similar to Figure 2, showing a modification;

Figure 4 is a view similar to Figure 1, showing another modification; and

Figure 5 is a section on the line V—V of 20 Figure 4.

My invention has relation to annealing leers, and more particularly to leers of the muffle type.

25 The object of my invention is to provide means of practical and efficient character whereby a leer of this type may be heated electrically in a manner to insure the maintenance of the desired temperatures throughout the different portions of the leer.

Referring first to that of my invention shown in Figures 1 and 2, the numeral 2 designates the annealing chamber of a glass annealing leer, and 3 a portion of the tunnel 35 part of the leer. The heating chamber 2 is provided with a series of internal flues 4 which extend entirely around the heating chamber and are preferably spaced longitudinally one from the other. These flues 40 are shown as formed of hollow tiles of any suitable character.

In accordance with my invention, each of these flues is filled with some material 5 which will act as a resistance conductor for electric currents. For this purpose, I employ a graphite in more or less comminuted form, or a mixture of carbon and silica commonly known as kryptol, or any other suitable material of this same general character. 50 Each flue is provided with terminals or electrodes 6 by means of which an electric current may be passed through the resistance material therein. In the construction shown in Figures 1 and 2, the electrodes or terminals are shown as extending into opposite

lower corners of the flues, the current being intended to divide and take two paths through the resistance material from one electrode to the other. The current flow between these two paths may be properly proportioned, either by regulating the character of the resistance mixture or its density. The electric connections leading to the electrodes are shown as grouped in cables, one of which is carried through a rheostat 7 by which the current may be controlled. I do not, however, limit myself to any particular arrangement of the electric circuits, as these may be arranged in any suitable manner known in the art and, if desired, the current flow for each flue may be capable of separate regulation by any well known means.

In Figure 3, I have shown my invention applied to a leer which is generally similar to that shown in Figures 1 and 2, except that the heating chamber 2^a has a flat instead of an arched top; the terminals or electrodes 6^a, instead of coming in at opposite corners of the furnace, come in at the central portion of the bottom of each flue, suitable insulating material 8 being interposed between them so as to cause the current to flow entirely around the flue from one terminal to the other.

In the form of my invention shown in Figures 4 and 5, instead of providing the heating chamber 2^b with a series of separate flues extending around it, I provide a continuous space 9 between the inner and outer walls of the chamber, which is filled with a resistance material. Preferably, this space 9 is of decreasing sectional area from the receiving to the discharge end of the heating chamber, so as to effect a gradual reduction in temperature from one end to the other. The terminals or electrodes 6^b are shown as arranged in multiple. Suitable openings 10 may be provided for the insertion, removal and replacement of the resistance material. These openings are normally closed by refractory plugs 11, or other suitable sealing means. If necessary, insulating material such as indicated at 12, in Figure 3, may be employed to prevent grounding of the current.

The advantages of my invention result from the provision of means whereby the leer may be electrically heated, the arrangement being such that the temperatures may be readily controlled and held at the desired

point. The use of electric heat for the purpose also eliminates all danger of injury to the ware being annealed, due to any products of combustion getting into the annealing chamber. The resistance material, being confined in an inclosed space or spaces, is excluded from the atmosphere, thereby preventing its combustion and enabling it to be used for an indefinite period.

10 It will be readily understood that my invention is susceptible of many other modifications within the spirit and scope of the appended claims.

I claim:

15 1. An annealing leer of the muffle type, having a heating chamber, and means for electrically heating said chamber, said means being of different characteristics in different portions of the chamber whereby different temperature conditions may be maintained in different portions thereof, substantially as described.

20 2. A glass annealing leer of the muffle type, having a resistance material in the

walls of its heating chamber, said material being of different conductivity in different portions of the furnace, and means for passing electric currents in multiple through such material, substantially as described.

3. An annealing leer of the muffle type, having a heating chamber and a tunnel in communication therewith, and means extending substantially entirely around the heating chamber for electrically heating the same, said means having different portions of its body of different characteristics to automatically regulate the current flow therethrough, substantially as described.

4. A glass annealing leer of the muffle type, having a resistance material in the walls of its heating chamber, said material being of different conductivity in different portions of the furnace, substantially as described.

In testimony whereof, I have hereunto set my hand.

HENRY L. DIXON.
